UNITED STATES PATENT OFFICE.

JOHN LOVETT, OF INDIANAPOLIS, INDIANA, ASSIGNOR TO RUBEN B. POWERS, EDGAR P. DENISON, JOHN B. DONGAN, AND AARON H. MOORE.

ROLLER-SKATE.

SPECIFICATION forming part of Letters Patent No. 311,841, dated February 3, 1885.

Application filed May 2, 1884. (No model.)

To all whom it may concern:

Be it known that I, JOHN LOVETT, a citizen of the United States, residing at Indianapolis, in the county of Marion and State of Indiana, have invented certain new and useful Improvements in Roller-Skates, of which the following is a specification.

My invention relates to that class of roller-skates in which the roller-frames are crimped to by the tilting movement of the foot-plate; and my invention consists in constructing the roller-frames and their supports, as fully described hereinafter, so as to secure a positive bearing upon each cramping-frame without interfering with the free movements of the latter, and without undue friction resulting from said movements.

The invention further consists in certain improvements in the details of this case.

In the drawings, Figure 1 is a side elevation, in part section, of a roller-skate embodying my improvements. Fig. 2 is a perspective view of the roller-frame. Fig. 3 is a perspective view of the bearing-bracket of the roller-frame. Fig. 4 is a section of the roller-frame at the point where the roller-shaft is connected, and Fig. 5 is a section on the line 12, Fig. 1.

The skate is provided with the usual foot-piece, A, to the under side of which, near each end, is bolted a bearing-bracket, B, consisting of a substantially L-shaped plate having at the outer end a rounded socket, s, and a terminal hood or guard, a, with an open mouth adjacent to the socket x. The inner downwardly-projecting portion of the bracket terminates in teeth b, which mesh with corresponding teeth, b', at the rear of the roller-frame D, and on a plane below the top of the frame. The roller-frame has an upwardly-projecting arm, d, terminating in a rounded head or knob, e, in a plane above the top of the frame, adapted to the socket x, and a finger, f, projects from the neck forward into the hood a. The body g of the frame D is of a box-like form, illustrated in the drawings open at the bottom and with a slot or opening, y, at the top, the under portion of the said top being convexed, as shown in Fig. 5, so as to afford a convex seat for a block of rubber

or other elastic material, F, which is clamped against said seat by a screw, G, passing through the block, through the slot y, and into the bracket B. Arms h extend laterally from the body g and forward, with their ends in line with the transverse portion or plug k, through which and through the ends of the arms extend the axle or axles m, upon which turn wheels I. Thus constructed, each bracket B has its bearings upon the wheel-frame D at two points which are upon a diagonal line, w, Fig. 1, each of said bearings being both a rocking and a rolling bearing, so that the foot-piece A may be both tilted and swung readily from one side to the other, which will result in swinging the roller-frame to one side or the other, thereby directing the movement of the skate to that side to which the foot-piece is tilted, as usual in skates of this character. It will be noticed, however, that there are no trunnion or pivot bearings, that the upper bearings, e x, are practically a ball-and-socket joint, and that the lower bearing is a rolling bearing and rocking bearing, the parts moving upon each other without friction, the lower bearing being below the top z of the frame B. The finger f holds the head e in its socket, while the contact of the lower bearing-pieces is maintained by the action of a spring, F, which tends to press the frame D toward the bracket B, but so yields readily to permit one to play upon the other. The rounded or convexed shape of the under side or bearing z upon the spring F tends to facilitate the rocking motion of one part upon the other without imparting increased compression to the spring as the angle of one part to the other is increased.

To permit the axle or axles to be readily detached, and yet securely held in place when removal is not required, I perforate transversely both the frame and the axle, and extend through such perforation the end i of a spring, N, secured to the frame at its opposite end. The pin i holds the axle in place, the spring preventing the pin from becoming displaced, but permitting it to be readily drawn out, when the axle may be removed.

As shown, the axle consists of two rods, with overlapping ends within the frame, the overlapping portions being perforated for the

passage of the single pin *i*, which thus secures both rods in place. The lower rear bearing of each bracket *B* may be a plain rounded face. It is, however, preferable to provide it with teeth, which tend to prevent slipping of one part upon the other, and the spring *F* may in some cases be dispensed with, the screw-pin *G* being brought against the convexed bearing *z*. It is preferable, however, to use the spring, which tends to maintain the parts in their central position until force is applied to alter their relations.

I claim—

1. The combination, in a roller-skate, of a frame supported by the rollers, and a bracket secured to the foot-piece of the skate and provided at one end with a socket adapted to engage with the knob at the end of an upwardly-projecting arm on said frame, and a lower rocking and rolling bearing at the opposite end of the bracket and frame below the top *z* of the frame, substantially as set forth.

2. The combination, in a roller-skate, of the roller-frame, a foot-piece provided with a bracket having at one end a pendent arm extending downward inside and below the top of the frame, and at the opposite end a socket adapted to receive the knob at the end of an upwardly-projecting arm on said roller-frame, and a screw-bolt extending into the bracket and clamping an elastic block against the roller-frame, substantially as set forth.

3. The combination of the bracket, the roller-frame having bearings on a diagonal line, as set forth, screw-pin *G*, and spring *F*, clamped by the screw against a convexed face, *z*, on the under side of the roller-frame, substantially as set forth.

4. The combination, with the roller-frame, of the bracket secured to the foot-piece having an outer bearing upon the frame, and with an inner downwardly-projecting arm terminating in teeth adapted to a toothed bearing at the inner side and below the top of the frame, the two bearings arranged to permit the roller-frame to swing on a diagonal line, substantially as set forth.

5. The combination of the frame having a box or recess to receive the spring *F*, screw holding the parts together, and bearings at the front and rear above and below the top of the frame, substantially as described.

6. The axle in two separate perforated parts, in combination with the frame having side arms and central box for the axle, and with holes to receive the end of a spring-key, substantially as described.

7. The combination, with the detachable axle perforated to coincide with the perforations in the frame, of a spring connected to the frame and terminating in a pin extending through both perforations, substantially as set forth.

8. The combination, with the axle in two sections with overlapping perforated ends, of a perforated frame receiving said ends, and a spring terminating in a pin extending through said perforations, substantially as set forth.

In testimony whereof I have signed my name to this specification in the presence of two subscribing witnesses.

JOHN LOVETT.
